(No Model.)

J. W. HOWELL.
SYSTEM OF ELECTRICAL DISTRIBUTION.

No. 377,488.

Patented Feb. 7, 1888.

UNITED STATES PATENT OFFICE.

JOHN W. HOWELL, OF NEW BRUNSWICK, NEW JERSEY.

SYSTEM OF ELECTRICAL DISTRIBUTION.

SPECIFICATION forming part of Letters Patent No. 377,488, dated February 7, 1888.

Application filed July 14, 1886. Serial No. 208,021. (No model.)

To all whom it may concern:

Be it known that I, JOHN W. HOWELL, of New Brunswick, in the county of Middlesex and State of New Jersey, have invented a certain new and useful Improvement in Systems of Electrical Distribution, of which the following is a specification.

This invention relates to the Edison system of electrical distribution, in which feeding-conductors extend from omnibus wires at the central station to the main or lighting conductors with which the translating devices are connected. In such a system it has heretofore been usual to run a pair of indicating-wires from the outer terminals of each feeding-circuit, where it joins the main conductors, to the central station, and there connect such wires to an indicator of electro-motive force, whereby the difference of potential at the end of each 15 feeder may be noted, and the feeders may be regulated to maintain the electro-motive force the same at the ends of all the feeders or throughout the system of main conductors.

The object of my invention is to dispense with the large number of electro-motive-force indicators required by this arrangement, these being expensive instruments, and to simplify the apparatus at the central station, while at the same time I provide efficient, convenient, 30 and exact means of indication of the electro-motive force at the end of each feeder.

My invention is illustrated in the annexed drawings.

Figures 1 and 2 are diagrams showing the principle of my invention applied to a two-wire system; Fig. 3, a more extended diagram showing the use of my invention in practice with the two-wire system; Fig. 4, a diagram showing the principle of the invention as applied to a three-wire or compensating system, and Fig. 5 a diagram showing the practical arrangement in the three-wire system.

Referring first to Fig. 1, 1 2 are omnibus wires. 3 4 represent the system of main or lighting conductors, and 5 6 and 7 8 are two feeding-circuits extending from said omnibus wires to different points of the main-conductor system. It will be seen that if a wire, 9, is brought from the outer to the inner terminal 45 of positive feeding-conductor 5, and a wire, 10, extends between the two terminals of posi-

tive feeding-conductor 7, and the two coils of a differential galvanometer, A, are included—one in wire 9, the other in wire 10—then, if the drop in electro-motive force on conductor 55 7 is the same as that on conductor 5, the two coils will equally affect the galvanometer-needle, and it will not be deflected. It will be understood, of course, that the electro-motive force is the same at all points on the omnibus 60 wires. Therefore if the pressure at the end of conductor 5 is constantly indicated by an absolute indicator and kept constant the drop on conductor 7 will always be indicated by the movements of the galvanometer-needle, 65 and feeding-circuit 7 8 may be regulated in accordance therewith.

In Fig. 1 an adjustable resistance, B, is shown in one side of each feeding-circuit for regulating the current in accordance with the 70 indications of the electro-motive-force indicators. Where a resistance is thus placed in one side only of each feeding-circuit, the method of indication just described is not perfectly accurate, because the drop in the different 75 feeders on the side having no resistance is not the same. Fig. 2, however, shows an arrangement which is equally efficient whether resistances are placed in one or in both sides of each 80 feeding-circuit. I have shown the resistances B in both sides. In this arrangement I employ a four-coil galvanometer, C, and between the terminals of each feeding-conductor a wire extends, which includes one of the galvanometer-coils. From positive conductor 5 extends 85 wire 9, from positive conductor 7 wire 10, from negative conductor 6 wire 11, and from negative conductor 8 wire 12. Each two coils connected with the same feeding-circuit oppose each other; also each two coils connected 90 with conductors of the same polarity of different feeding-circuits oppose each other. Therefore the sum of the drops in electro-motive force on the two conductors of one feeder opposes in the differential galvanometer the sum 95 of the drops on two conductors of the other feeder, and the differential indicator thus compares the sum of the drops on one feeder with the sum of the drops on the other; and if one of said feeders is provided with an absolute 100 indicator of electro-motive force connected between its outer terminals, so that it can be

regulated to maintain the right electro-motive force, the galvanometer indications will show the condition of the other feeder, so that it also can be regulated.

5 A two-wire system with three feeders, 5 6, 7 8, and 13 14, is shown in Fig. 3. D is an indicator of electro-motive force, preferably such as is set forth in my Patent No. 339,058, dated March 30, 1886. This indicator is connected with the usual indicating or pressure wires, 15 16, extending from the outer terminals of the standard feeder 5 6 to the central station.

15 C and C' are the four-coil differential galvanometers or comparative indicators. These are wound and connected as already described with reference to Fig. 2, the wires 9 11 extending from the outer terminals of 5 6 to the station and branching at a a, so as to extend 20 to both galvanometers C C', and thence to the omnibus wires, while 10 12 from 7 8, and 17 18 from 13 14 extend, respectively, to the two galvanometers, and thence also to the omnibus wires. Indicator D enables the pressure 25 at the terminals of feeder 5 6 to be always known, and indicators C C' compare the loss there with that on 7 8 and 13 14, respectively, as already fully explained.

30 Fig. 4 illustrates in a simple manner a three-wire system. 1, x, and 2 are respectively the positive, middle or compensating, and negative omnibus conductors; 3, x', and 4, three similar conductors of the lighting or main conductor system; 5, x⁴, 6, the conductors of the standard feeder, and 7, x⁵, 8, those of another feeder. Wires 9 x⁴ from the positive and neutral wire of the standard feeder extend to the corresponding omnibus conductors, and include two coils of the differential galvanometer C. Wires 10 x⁵ extend in the same way 35 from the positive and neutral wires of the other feeder, and include the other two coils of the galvanometer. Wires 9 and x⁴, connected with the same feeder, are wound to act together; so, also, are wires 10 and x⁵. Wires 10 and 9, which are connected with conductors of the same polarity, oppose each other; so, also, do wires x⁴ and x⁵. Thus the galvanometer, arranged as shown in Fig. 4, compares the 40 algebraic sum of the drops in electro-motive force on the positive and neutral wires of one feeder with the algebraic sum of the drops on the corresponding wires of the other feeder; and the pressure on one feeder being constantly 45 known, that on the other is readily seen by this comparison. It should be understood that currents in the neutral wire when flowing from omnibus to mains are considered positive, and when flowing from mains to 50 omnibus are considered negative.

55 In practice the instruments are arranged to compare the drops on positive and neutral wires of the standard feeder with those of each of the other feeders, and also the drops on negative and neutral wires of the standard feeder with those of each of the other feeders. This is shown in Fig. 5. The feeding-con-

ductors themselves are omitted in this figure to avoid confusion from multiplicity of lines. It will be readily understood that they extend 70 from the omnibus wires 1 x 2 to the respective points on the mains 3 x' 4 at which the indicating-wires 9 x⁴ 11, 10 x⁵ 12, and 17 x⁶ 18 are shown as connected. The coils of galvanometer C are included, one in a wire, 11, from 75 negative conductor of standard feeder, another in wire x⁴ from neutral wire thereof, and one in wire 12 from negative wire of a second feeder, another in wire x⁵ from neutral wire thereof. Galvanometer C' has its coils 80 similarly divided between wires from positive and neutral of standard and positive and neutral of the second feeder. Galvanometers C and C' are similarly connected between the two sides of the standard feeder and those of 85 the third feeder. A pair of absolute electro-motive-force indicators, D D', are employed, connected, respectively, with the two sides of the standard feeder. The differential galvanometers being wound as explained with reference 90 to Fig. 4, they act to compare the drops in electro-motive force on the different feeding-conductors with that on the standard, as was also before explained.

What I claim is—

95 1. In a system of electrical distribution the combination, with conductors of two feeding-circuits, of indicating-conductors extending from their outer to their inner terminals, and a differentially-wound indicating-instrument 100 having its coils divided between the indicating-conductors of the two feeding-circuits, substantially as set forth.

2. In a system of electrical distribution, the combination, with the conductors of two feeding-circuits, one of which is a standard circuit, of indicating-conductors extending from the outer to the inner terminals of each of the conductors of said feeding-circuits, and a four-coil differential galvanometer having one set of 110 coils included in each of said indicating-conductors, substantially as set forth.

3. In a system of electrical distribution, the combination, with omnibus wires, a system of main or lighting conductors, and two or more 115 feeding circuits connecting them, of an absolute indicator of electro-motive force connected with the outer terminals of one of said feeding-circuits, (the standard circuit,) indicating-conductors extending from the outer to the 120 inner terminal of each conductor of said standard circuit, indicating-conductors extending from the outer to the inner terminal of each conductor of each of the other feeding-circuits, and four-coil differential galvanometers, each 125 having two coils in the indicating-wires from the standard circuit and two coils in the indicating-wires from one of the other feeding-circuits, substantially as set forth.

4. In a three-wire system of electrical distribution, the combination, with omnibus wires, a system of main or lighting conductors, and two or more feeding-circuits connecting them, of two absolute indicators of electro- 130

motive force connected, one with the outer terminals of each side of one of said feeding-circuits, (the standard circuit,) indicating-conductors extending from the outer to the inner terminal of each of the three conductors of said standard circuit, indicating-conductors extending from the outer to the inner terminal of each of the three conductors of each of the other feeding-circuits, four-coil differential galvanometers, each having two coils in the indicating-conductors from the positive and neutral conductors of the standard circuit and two coils in the indicating-conductors from the corresponding conductors of one of the other feed-

ing-circuits, and other four-coil differential 15 galvanometers, each having two coils in the indicating-conductors from the negative and neutral conductors of the standard circuit and two coils in the indicating-conductors from the corresponding conductors of one of the other 20 feeding-circuits, substantially as set forth.

This specification signed and witnessed this 7th day of July, 1886.

JOHN W. HOWELL.
